UNITED STATES PATENT OFFICE.

ERNST KRAHNSTÖVER, OF MILWAUKEE, WISCONSIN.

FABRIC-STRETCHER.

No. 890,240.

Specification of Letters Patent.

Patented June 9, 1908.

Application filed November 24, 1906. Serial No. 344,827.

To all whom it may concern:

Be it known that I, ERNST KRAHNSTÖVER, a citizen of the United States, and resident of Milwaukee, in the county of Milwaukee, 5 and State of Wisconsin, have invented certain new and useful Improvements in Fabric-Stretchers; and I do hereby declare that the following is a full, clear, and exact description thereof.

10 The invention consists in what is herein shown, described and claimed; its object being to provide simple, economical and efficient stretchers for cleaned curtains, carpets and other textile fabrics, said stretchers being especially designed for professional 15 cleaning establishments.

Figure 1 of the accompanying drawings represents a plan view of a stretcher in accordance with my invention having a longitudinal pin-bar thereof partly broken away; Fig. 2, a vertical transverse sectional view of the stretcher, indicated by lines 2—2 in Fig. 1, and Fig. 3, a vertical longitudinal section view of a fragment of said stretcher 25 indicated by lines 3—3 in said Fig. 1.

Referring by letter to the drawings, A indicates each of the side rails, and B each of the end rails of a preferably rectangular frame, that may be mounted on casters, if 30 desirable, to facilitate moving the same from place to place in a cleaning establishment. At suitable intervals longitudinally of the frame, the same is provided with transverse braces C fastened at their ends to the side rails of said frame.

Fast on the frame parallel to one of the side-rails thereof and over the same is a partly beveled bar D having its bevel portion provided with a series of upwardly projecting pins b at suitable regular intervals apart, and supported on the end rails and intermediate braces of said frame is a pin-bar E similar to the one D aforesaid. The pin-bar E is free to slide on said end rails and braces of the aforesaid frame. In suitable rigid connection with the pin-bar E to depend therefrom are brackets each of which has lugs c engaged by horizontal guides d in connection with the frame-braces C, and 50 each bracket has its lower end in the form of a nut-sleeve e engaged by a screw-spindle F for which a bearing-hanger f is provided in connection with the guides aforesaid, the two spindles shown being miter-gearied to 55 a shaft G supported in bearings g depending from braces C to which they are secured.

Shown on the outer end of the shaft G is a crank H common to said shaft and other shafts hereinafter described, the outer end of each shaft being squared to engage a corresponding socket in the crank. 60

In sliding support on the upper horizontal portions of the pin-bars D, E, clear of the pins projecting from the bevel portions of said bars, are similar bars I, J, although one 65 of these transverse pin-bars may be stationary if desirable. The bars I, J, as herein shown are each provided with depending brackets, similar to those aforesaid in connection with the pin-bar E, and the grooved 70 lugs c' of these brackets are engaged by guides d' attached to the side rails of the frame aforesaid and to stringers K in said frame between the end rails and transverse braces of the same. The nut-sleeve terminals e' of the brackets having the lugs c' are 75 engaged by screw-spindles L and bearing-hangers f' for these spindles are provided in connection with the guides d' aforesaid. The spindles L are miter-gearied in pairs to shafts 80 M for which hangers are provided in connection with side rails and stringers of the frame above specified.

In practice, the fabric to be stretched and dried is caught at the longitudinal edges 85 thereof on the pins of the bars D, E, the latter bar having been suitably adjusted as a result of turning the shaft G in the proper direction. The fabric having been caught on the pin-bars D, E, rotary motion is again 90 imparted to the shaft G to take up slack and properly stretch said fabric, the adjustment of the pin-bar E to this end being determined by the sag and strength of the aforesaid fabric. The ends of the fabric are now caught 95 on the pins of the bars I, J, one or both of these bars having been suitably adjusted by turning of the relative shaft or shafts M in the proper direction. The stretcher and fabric therewith may be placed in a dry room to 100 hasten the drying of said fabric, it being understood that this fabric is stretched in a moist condition, and that my invention is particularly applicable as a stretcher for lace curtains and the like preliminary to drying 105 the same after being cleaned.

I claim:

1. A fabric-stretcher comprising an angular frame provided with braces and stringers, a pair of partly beveled pin-studded bars on 110 the frame, another pair of similar bars crossing those aforesaid clear of the beveled pin-

studded portions of same, guides in connection with frame-braces, nut-sleeve brackets depending from an under pin-bar in sliding engagement with the guides, screw-spindles 5 engaging the sleeves of the brackets, a crank-spindle in gear with those aforesaid, other guides in connection with a side-rail and stringers of the frame, brackets similar to those aforesaid in sliding engagement with 10 the latter guides and suspended from an upper pin-bar, screw-spindles engaging the nut-sleeves of the latter brackets, and a crank-spindle in gear with the latter screw-spindles.

2. A fabric-stretcher comprising an angular frame provided with braces and stringers, 15 a pair of partly beveled pin-studded bars on the frame, another pair of similar bars crossing those aforesaid clear of the beveled pin-studded portions of same, guides in connection with frame-braces, nut-sleeve brackets 20

depending from an under pin-bar in sliding engagement with the guides, screw-spindles engaging the sleeves of the brackets, a crank-spindle in gear with those aforesaid, other guides in connection with side rails and 25 stringers of the frame, brackets similar to those aforesaid in sliding engagement with the latter guides and suspended from the upper pin-bars, screw-spindles engaging the nut-sleeves of the latter brackets, and crank-spindles in gear with the latter screw-spindles. 30

In testimony that I claim the foregoing I have hereunto set my hand at Milwaukee in the county of Milwaukee and State of Wisconsin in the presence of two witnesses.

ERNST KRAHNSTÖVER.
